WILLIAM DIEBEL, OF PHILADELPHIA, PENNSYLVANIA.

SPARKING PLUG FOR EXPLOSIVE-ENGINES.

No. 866,631.

Specification of Letters Patent.

Patented Sept. 24, 1907.

Application filed July 13, 1906. Serial No. 326,010.

To all whom it may concern:

Be it known that I, WILLIAM DIEBEL, a citizen of the United States, residing at Philadelphia, county of Philadelphia, and State of Pennsylvania, have invented a certain new and useful Improvement in Sparking Plugs for Explosive-Engines, of which the following is a specification:

My invention relates to a new and useful improvement in sparking plugs for explosive engines, and has for its object to provide an exceedingly simple and effective construction in which an explosion chamber of large capacity is formed so that at each explosion of the gas under pressure the sparking points will be cleaned of accumulations of soot or oil by the outward rushing of the gas from this explosion chamber.

A further object of my invention is to effectually insulate the central conductor and sparking point from the metal plug without placing porcelain or other insulating material within the cylinder or below the fire line, thus overcoming the serious disadvantage which have heretofore been experienced in the cracking or breaking away of such insulating material and the falling of the same within the cylinder, which would of necessity injure the piston and cylinder.

With these ends in view, this invention consists in the details of construction and combination of elements, hereinafter set forth and then specifically designated by the claims.

In order that those skilled in the art to which this invention appertains may understand how to make and use the same, I will describe its construction in detail, referring by letter to the accompanying drawing forming a part of this specification, in which—

Figure 1 is a bottom plan view of one form of my improved construction. Fig. 2, a vertical section thereof. Fig. 3, a bottom plan of a slightly modified form of my improvement. Fig. 4, a vertical section thereof. Fig. 5, a bottom plan of a still further modified form of my improvement. Fig. 6, a vertical section thereof.

In carrying out my invention as embodied in Figs. 1 and 2, A represents the metal body of a plug, which is adapted to receive a wrench, and B is the threaded nipple extending downward from this body by which the plug is secured in the head of the cylinder in the usual manner. The nipple is hollow forming a chamber, and the body portion of the plug has an enlarged cavity C formed therein which serves the double purpose of increasing the capacity of the chamber so as to make a choked explosion which will cause the exploded gases to rush past the sparking points with such violence as to clean the same of accumulated soot or oil; and the further object of this enlarged chamber is to provide sufficient space around the head D of the central conductor E to prevent the jumping of the cur-

rent from this head to the metal plug, as is clearly shown in Fig. 2.

The conductor E passes through an insulating plug F of rolled mica or other suitable material and has a series of mica insulating washers G interposed between the head D and the upper wall of the cavity C, while around the upper portion of the central conductor E is placed a porcelain or other insulating block H, a suitable jam nut I being run upon the upper threaded end of the conductor and jammed against the block H thus holding the parts in place.

J is the ordinary binding nut run upon the upper end of the conductor E by which the terminal of the electric source is clamped in place.

K represents the central sparking point, which extends downward from the head D flush with the lower edge of the nipple, and L is the other sparking point which is secured to the bottom edge of the nipple and extends crosswise in close proximity to the sparking point.

It is to be noted that no insulating material is placed around the sparking point K, and as in my improved construction none is needed on account of the chamber within the nipple being of sufficient size to preclude the possibility of the jumping of the current from this point to the walls of the metal plug, and the danger which has heretofore existed of the insulating material cracking and breaking away on account of the heat to which it is subjected and falling into the cylinder where it will be ground into the walls of the cylinder and the piston rings, thus cutting and scarring the cylinder and rings is entirely obviated.

In Figs. 3 and 4 a slightly modified form of my improvement is shown in which the interior bore of the nipple B is of the same diameter as the bore in the body A, making a straight cylindrical chamber of sufficient size to preclude the possibility of the current jumping from the head D or the sparking point K to the walls of the metal plug. The diameter of this construction is the same as that just described in connection with Figs. 1 and 2.

In Figs. 5 and 6 a further slight modification of my improvement is embodied, in which the body A' has a double bore of different diameters, the upper portion being adapted to receive the porcelain insulator H' which shoulders upon the ledge formed by the small diameter of the lower portion of the bore which constitutes the explosion chamber a, a heat insulating washer G' being interposed between the porcelain H' and the ledge which covers the bottom of the porcelain and prevents an undue amount of heat being transmitted thereto. This washer also serves to hold the porcelain in place even though it should become cracked or broken. b is a threaded collar adapted to fit over the tapered portion of the porcelain H' and 110

be threaded into the upper end of the body A', thus firmly holding the porcelain in place within the body. The chamber a has its outer circumference threaded for securement in the cylinder in the usual manner, 5 and the lower end of this chamber is closed with the exception of the small opening d through which the sparking point K' projects, L' being the other sparking point secured to the plug. The central conductor E' projects through the porcelain insulator and is se-
10 cured in place by the jam nut I'. In this construction the central conductor and sparking point may be removed without the removal of the metal plug from the cylinder and the explosion chamber a is of such capacity relative to the opening d therefrom that
15 when an explosion takes place the gas contained within the chamber will be shot through this opening with such violence as to thoroughly clean the sparking points.

Having thus fully described my invention, what I claim as new and useful, is—

In combination, a body having a threaded upper end, the threaded lower portion having a small opening therein, a sparking point extending inwardly from the wall of the lower opening, a shoulder in the body, a heat insulating washer resting on the shoulder, a porcelain insulator fitting to the bore of the body and resting on the washer, said washer and porcelain insulator having coinciding apertures, and said insulation terminating at the washer, a conductor extending through the aperture of the insulator and washer having a sparking point terminating near the 25
sparking point in the wall of the body and a threaded collar in the body to bear on the porcelain insulator.

In testimony whereof, I have hereunto affixed my signature in the presence of two subscribing witnesses.

WILLIAM DIEBEL.
